Primary Examiner — Calvin E Vansant*Assistant Examiner* — Mark T. Philipp*(74) Attorney, Agent, or Firm* — Workman Nydegger(57) **CLAIM**

The ornamental design for a fluid pump, as shown and described.

DESCRIPTION

FIG. 1 is an elevated facing view of my new design for a fluid pump;

FIG. 2 is an elevated rear view thereof;

FIG. 3 is an enlarged view of the region indicated in FIG. 2 by the long-dash-short-dash broken lines;

FIG. 4 is an elevated left view thereof;

FIG. 5 is an elevated right view thereof;

FIG. 6 is a top plan view thereof;

FIG. 7 is an enlarged view of the region indicated in FIG. 6 by the long-dash-short-dash broken lines;

FIG. 8 is bottom plan view thereof;

FIG. 9 is a bottom, left, facing perspective view thereof; and,

FIG. 10 is a top, left, rear perspective view thereof.

Broken lines in the drawings are for the purposes of illustrating environmental structures around the fluid pump only and form no part of the claimed design. The dash dot broken lines on FIGS. 2, 3, 6 and 7 are provided to define the enlargement regions in each and form no part of the claimed design.
